CLAIM

We claim the ornamental design for a pocket for a handheld electronic device, as shown and described.

DESCRIPTION

FIG. 1 is a front perspective view of a pocket for a handheld electronic device;

FIG. 2 is a back perspective view of the pocket for a handheld electronic device;

FIG. 3 is a front plan view thereof;

FIG. 4 is a left elevation view thereof;

FIG. 5 is a back plan view thereof;

FIG. 6 is a right elevation view thereof;

FIG. 7 is a top plan view thereof; and,

FIG. 8 is a bottom plan view thereof.

The dashed lines in the drawings represent stitching which forms part of the claimed design.
